UNITED STATES PATENT OFFICE.

SHIGEO MORITA, OF SAN FRANCISCO, CALIFORNIA.

DESIGN FOR AN INCENSE BURNER.

Application filed October 16, 1923. Serial No. 7,510. Term of patent 3½ years.

To all whom it may concern:

Be it known that I, SHIGEO MORITA, a subject of the Emperor of Japan, and a resident of San Francisco, county of San Francisco, State of California, have invented a new, original, and ornamental Design for an Incense Burner, of which the following is a specification, reference being had to the accompanying drawing, forming part thereof.

The figure is a perspective view of the incense burner constituting my new design.

I claim:

The ornamental design for an incense burner substantially as shown.

SHIGEO MORITA.
